UNITED STATES PATENT OFFICE.

WILLIAM EVERETT GRISWOLD, OF NEW YORK, N. Y.

DENTAL SECURING DEVICE.

SPECIFICATION forming part of Letters Patent No. 733,320, dated July 7, 1903.

Application filed June 14, 1902. Serial No. 111,669. (No model.)

To all whom it may concern:

Be it known that I, WILLIAM EVERETT GRISWOLD, a citizen of the United States, residing at New York, in the county of New York and State of New York, have invented 5 certain new and useful Improvements in Dental Securing Devices; and I do hereby declare the following to be a full, clear, and exact description of the invention, such as will enable others skilled in the art to which it 10 pertains to make and use the same.

My invention relates to dentistry. Its object is to provide dental securing devices that consist, essentially, of interlocking spring 15 members adapted to be applied to opposing or opposite parts of the denture.

In the accompanying drawings, Figure 1 is a perspective of a portion of a jaw with an attaching device above ready to be put in place. Fig. 2 are detail perspectives of two complementary attaching devices known as the "V-fastener." Fig. 3 is a division of an attaching device with an accompanying detail of a tension-spring. Fig. 4 is a perspective of the complementary securing devices of a T-fastening. Fig. 5 is a side elevation of a form of coil-spring adapted to be used. Fig. 6 is a section of the two parts joined. Fig. 7 is a side elevation of a form of coil-spring. Fig. 8 is a perspective of the complementary parts of the L-shaped fastening devices. Fig. 9 is a vertical section of a spring-fastening, together with an enlarged detail of a spring used as a tension device. Fig. 10 is a side elevation of a tooth with one part of a form of fastening secured to it, and Fig. 11 is a section of a tooth and fastening secured.

In the drawings I have illustrated what may 40 be roughly termed three forms of fastenings—a V-fastening, a T-fastening, and an L-fastening. In all these fastenings I provide for a male member and a female member and an interlocking feature. In the V-fastening 45 at Figs. 2 and 3 I have illustrated the female member as having a series of corrugations on the side and the male member as having ribs on the side which are adapted to engage the corrugations, the character of the engagement depending upon the distance the male member is forced into the female member. I may of course vary the ratio of the ribs and

corrugations or recesses. This device is made of a piece of spring metal bent into what may be roughly termed "V" shape, so 55 that the apex of the V when the male member is forced into the female member may close the opening in that member, forming a compact fastener, though in some instances I may reverse the relative arrangement. The bottom 60 of the male member may be closed and the top of the member inclosing it may be covered over with a plate secured after the parts are placed so that the whole fastening is closed in. In Fig. 3 I have shown the V member with a 65 spring. (Illustrated in detail below.) The spring may serve to tension the sides of the male member to force it out into an assured and firm contact with the corrugations of the female member where a peculiarly tight fit is 70 desired. In the T-shaped member and the L-shaped member of Figs. 4 to 9 I provide likewise for interlocking features; but in these devices I have illustrated salient points of a tension-spring or coil-spring with flaring 75 arms as preferably passing through openings in the side of the male member, so that the points may press out into the corrugations of the female member, and thus secure the two together, as especially illustrated in the section of Fig. 6. The L and T devices have wings or flanges on the sides for the purpose of securing them to a crown, root-cap, or other feature and forming an attaching-base.

In the drawings, 1 represents the male V 85 member; 2, the female member; 3, corrugations in the side of the female member; 4, ribs formed on the outside of the male member.

5 is a spring adapted to be applied, if de- 90 sired, to the male member.

6 is a closed bottom of the male member.

7 is a bevel shown on the top of the male member. There may be a corresponding bevel on the female member.

8 is the body of the male T-shaped member; 9, the body of the female T-shaped member; 10, corrugations of that member; 11, perforations in the sides of the male member; 12, a coiled spring having its flaring ends bent to 100 form salient points 13, which project through the perforations 11 and engage the corrugations or recesses 10. 14 is another form of coiled spring having salient points 15. This

spring may be used instead of the spring 12, though requiring the perforations to be placed lower in the sides of the male members. These binding-springs and the one described hereinafter illustrate some of the forms which may be applied and indicate that the form of the spring is subject to many modifications.

16 is a bottom, which may be integral with the male member; 17, a plate which may be soldered on the top of the member inclosing it, thus covering the two devices when secured together.

18 represents wings or flanges on the side of the securing devices adapted to be attached to the base of a root, crown, or cap.

In Fig. 8 I have applied the reference-letters as in the description and illustration preceding of the T-shaped fastener, Figs. 4 and 6.

20 In Fig. 9 the section may be regarded as a vertical section looking toward the front of the male member of Fig. 8. The figure is purposed merely to show the relative position of the modified spring 19 with its salient points 20.

25 In Fig. 10, 21 is a tooth. 22 is a slightly-modified male member of a T-shaped fastening secured to the tooth, the rounded sides of the fastening permitting the perforations 11 to show.

30 In Fig. 11, 21 is a section of a tooth, with the male member 8 and the spring 19 in position, illustrating the manner in which a long wing or flange may pass around the curve of a tooth or crown to secure a firmer attachment or add a base.

35 In Fig. 1, 23 is a wire to which is soldered at opposite ends two female members 2 of the V-shaped fastening. The wire 23 may be 40 closed in vulcanite or soldered to a saddle, and the female members may then be forced down over the male members 1, one of which is shown attached to a crown 25, the other to a root-cap 26, both being shown in place on 45 a portion of the jaw (or a model) 24. The beveled edges of the male member permit the user to readily find the proper position in placing the vulcanite or saddle, especially when the female member is correspondingly 50 beveled or flared. Hitherto I have described these spring-fastenings with general reference to the common features.

55 There are specific features of detail in the fastening of Figs. 1, 2, and 3 which require further description. The female member 2 has, as illustrated, a back 30, which may form an attaching device, though it is apparent that flanges or wings similar to the flanges or wings 18 may, if desired, be secured to any 60 part of the V-fastening to form an additional base or to give greater security in a difficult position. I have shown such an attached wing at 29, Fig. 1. This wing is soldered to the apex of the male member, and then the 65 wing is soldered to the side of the crown. On the opposite side the male member is shown

as soldered to the root-cap. The member 2 has also two converging sides 31 and 32, which may yield on the introduction of the male member, the narrow opening between the 70 sides being closed by the apex of the male member. 33 indicates an upward bend or flare given the metal, so that it may more readily take over the beveled portion 7 of the male member when applied as illustrated in 75 Fig. 1, for example. In the member 1 there are two diverging sides 34 and 35, which diverge from the apex 36. The diverging sides are bent to form two approaching lips 37 and 38 with a sufficient interval to provide for 80 the desired spring of the metal. When the male member is applied to the female member as previously described, the apex 36 will project slightly through the opening between the sides 31 and 32 of the member 2, while 85 the lips 37 and 38 will lie against the flat back 30, so that the member 1 may readily be forced into the member 2 without having any sharp edges of the member 1 interfere with such fit, and at the same time there is 90 provided a solid supporting-back for the combined members as thus joined. I have shown ribs 4 on the member 1 and have also in Fig. 3 illustrated a simple spring which may tension the member 1 against the sides of the 95 member 2 when in place. It is obvious that instead of the ribs 4 I may provide the perforations 11, as illustrated in Figs. 4 to 10, and apply the coiled spring with salient points, as illustrated in those figures.

100 In Fig. 11, as described, the application and use of the wings are illustrated. These wings facilitate soldering to the crown. The wings on the male member lie upon and embrace the female member and close in the whole, 105 so that it may be finished smoothly. The wings form a clasp which extends partially around the tooth and may be used as a surface to build porcelain against in making a porcelain denture, so as to give a close denture between the removable parts and the stationary crown. They also make the work more rigid and strengthen the denture to resist lateral strain.

110 Having fully described my invention, what I claim is—

1. A dental spring-metal securing device comprising a female member having converging sides, a male member having diverging sides and adapted to close the opening between the converging sides of the female member.

2. A dental spring-metal securing device comprising a female member having converging sides, a male member having diverging sides, and complementary interlocking ribs and recesses.

3. A dental spring-metal securing device comprising a female member having converging sides, and a male member having diverging sides and approaching lips.

4. A dental spring-metal securing device

comprising a female member, a substantially V-shaped male member, adapted to fit into and be inclosed by the female member and to close the opening between the sides of the 5 female member, and means for closing the top and bottom of the combined members.

5. A dental spring-metal fastening comprising a male member having perforations in its sides, a female member having corruga-
10 tions or recesses in its sides, and a spring bent to present salient points through the

perforations to engage the corrugations or recesses.

6. A dental securing device comprising complementary ribbed and recessed parts, 15 and a binding-spring.

In testimony whereof I affix my signature in presence of two witnesses.

WILLIAM EVERETT GRISWOLD.
